UNITED STATES PATENT OFFICE.

CONSTANT T. CUNDALL, OF STONINGTON, CONNECTICUT, ASSIGNOR, BY MESNE ASSIGNMENTS, TO C. B. COTTRELL & SONS COMPANY, OF NEW YORK, N. Y., A CORPORATION OF DELAWARE.

WEB-FOLDING MACHINE.

1,187,974.

Specification of Letters Patent. Patented June 20, 1916.

Application filed November 29, 1913. Serial No. 803,735.

To all whom it may concern:

Be it known that I, CONSTANT T. CUNDALL, a citizen of the United States, and resident of Stonington, in the county of New London and State of Connecticut, have invented a new and useful Improvement in Web-Folding Machines, of which the following is a specification.

The object of this invention is to provide manual means for controlling the surface speed of one or more of the web feed rolls of the web feeding mechanism so that all of the web sections may be driven at the desired speeds to insure the proper association of the web sections without interfering with the operation of the machine.

A practical embodiment of my invention is represented in the accompanying drawings, in which—

Figure 1 is a section through so much of a web folding machine as will give a clear understanding of the invention, Fig. 2 is a view in front elevation of the same, Fig. 3 is an enlarged detail section showing the manual means for expanding and contracting the web feed roll to vary its surface speed, and Fig. 4 is a detail cross section taken in the plane of the line A—A of Fig. 3.

Two wide webs 1 are shown as passing over the slitting roll 2 where they are separated into a plurality of superposed web sections by the slitters 3. The plurality of superposed web sections are then passed around the single turners 4 and as they leave the points of the said turners the superposed web sections pass between the pairs of rolls 5, 6. The superposed web sections then pass around a plurality of feed rolls 7 on their way to the pair of rolls 8, 9, where they are associated. In the present instance I have shown two of these intermediate feed rolls 7 acting upon each pair of superposed web sections as it passes from the pair of rolls 5, 6, to the pair of rolls 8, 9. A cross shaft 10 is driven from the vertical drive shaft 11 through the bevel gears 12, 13.

Each pair of rolls 5, 6, is driven from the cross shaft 10 through the bevel gears 14, 15, and intermeshing spur gears 16, 17.

The slitting roll 2 is driven from the shaft 10 through the train of gears 18, 19, 20, 21, 22, 23, and the shaft 24 of the slitters 3 is driven from the shaft 25 of the slitting roll 2 through the gears 26, 27.

The means for driving the web feed rolls 7 for each pair of superposed web sections is herein shown as the train of gears 28, 29, 30, 31, 32. I will proceed to describe the structure of one of these feed rolls 7 and 60 the manual means for expanding and contracting the same for varying its surface speed, it being understood that the other feed rolls 7 are similar in construction and operation. 65

The shaft of the feed roll 7 is denoted by 33, which shaft is mounted to rotate in suitable bushings 34, 35, fixed against rotative movement in the machine frame.

The feed roll itself comprises a cylindrical 70 shell 36 divided longitudinally as shown at 37 to permit the expansion and contraction of the shell. This shell is provided with split contracting rings 38, 39, surrounding its ends. 75

End blocks 40, 41, are keyed to the shaft 33 to slide lengthwise thereof, which end blocks are provided with tapered portions 42, 43, respectively. These tapered portions enter the opposite ends of the shell 36. 80 Manual means are provided for moving these end blocks 40, 41, toward and away from each other for expanding and contracting the shell 36, which means is shown herein as comprising yokes 44, 45, having oppositely arranged pairs of shoes 46, 47, located in circumferential grooves 48, 49, in the end blocks 40, 41. These yokes have a screw threaded engagement with the bushings 34 as shown at 50, 51, and are also 85 provided with gears 52, 53, which mesh with pinions 54, 55, fixed on a cross shaft 56 mounted in the machine frame. This shaft 56 is provided with a suitable handle 57. The turning of the handle 57 in one direction will force the end blocks 40, 41, toward each other and thereby expand the shell 36 of the roll, increasing the diameter of the roll and increasing its surface speed. By turning the handle 57 in the other direction, the end blocks 40, 41, will be moved away from each other permitting the shell 36 of the roll to contract and thus lessen the diameter of the roll and thereby decrease its surface speed. 95 100 105

For supporting the shell on the shaft intermediate the ends of the shell and for keying the shell to the shaft, I provide a centrally arranged interior collar 58, diametrically through which collar and shaft a pin 110

59 is passed, one end of which pin extends into the shell 36 opposite the slit 37 and the other end of which pin projects into the said slit.

5 It will be seen that the spring contracting rings 38, 39, not only serve to assist in the contraction of the shell 36 of the roll when the end blocks 40, 41, are moved outwardly away from each other, but also serve to reinforce the ends of the shell and prevent the distortion of the shell when the end blocks are moved inwardly toward each other.

10 From the above description, it will be seen that one or more of the feed rolls may be adjusted to the desired surface speed without interfering with the main drive of the machine and rolls, thus insuring the proper driving effect upon the web section or sections to properly adjust the sections by accelerating and retarding their speed so as to bring all of the web sections into exact register at the assembling rolls 8, 9.

15 While I have shown and described the feeding and slitting of two wide webs into a plurality of superposed web sections, it is to be understood that the invention may be used in connection with one or more wide webs and sections slit therefrom.

20 What I claim is:—

25 30 1. Web feeding mechanism including means for feeding a plurality of web sections, associating means therefor, web feed rolls for each of said sections, and manual means for independently expanding the rolls to change their respective surface speeds for insuring the proper feeding and association of the web sections.

35 40 2. Web feeding mechanism including means for feeding a plurality of web sections, associating means therefor, normally contracted web feed rolls for each of said sections and manual means for independently expanding the rolls to change their respective surface speeds for insuring the proper feeding and association of the web sections.

45 50 3. Web feeding mechanism including means for feeding a plurality of web sections, associating means therefor, longitudinally divided web feed rolls for each of said sections and manual means for independently expanding the rolls to change their respective surface speeds for insuring the proper feeding and association of the web sections.

55 60 4. Web feeding mechanism including means for feeding a plurality of web sections, associating means therefor, normally contracted longitudinally divided web feed rolls for each of said sections and manual

means for independently expanding the rolls to change their respective surface speeds for insuring the proper feeding and association of the web sections.

5 In web feeding mechanism, a web 65 feed roll including a shaft, a cylindrical shell, divided longitudinally, means for supporting the shell on the shaft intermediate the ends of the shell and for keying the shell to the shaft, and blocks movable along the shaft having oppositely tapered portions engaging the ends of the shell and manual means for moving the end blocks in opposite directions for expanding the shell to change its surface speed.

6 In web feeding mechanism, a web feed 75 roll including a shaft, a cylindrical shell divided longitudinally, means for supporting the shell on the shaft intermediate the ends of the shell and for keying the shell to the shaft, end blocks movable along the shaft having oppositely tapered portions engaging the ends of the shell, fixed bushings, yokes loosely engaging the end blocks having screw threaded engagements with said bushings and manual means for turning the yokes to move the end blocks in opposite directions for expanding the shell to change its surface speed.

7 In web feeding mechanism, a web feed 85 roll including a shaft, a cylindrical shell divided longitudinally, means for supporting the shell on the shaft intermediate the ends of the shell and for keying the shell to the shaft, end blocks movable along the shaft 95 having oppositely tapered portions engaging the ends of the shell, fixed bushings, yokes loosely engaging the end blocks having screw threaded engagement with the said bushings and a hand wheel geared to said 100 yokes for turning them to move the end blocks in opposite directions for expanding the shell to change its surface speed.

8 In web feeding mechanism, a web feed 105 roll including a cylindrical shell divided longitudinally, end blocks having oppositely tapered portions engaging the ends of the shell, split spring contracting rings surrounding both ends of the shell and a common means for moving the end blocks in opposite directions to expand the shell for changing its surface speed.

110 In testimony, that I claim the foregoing as my invention, I have signed my name in presence of two witnesses, this twenty sixth 115 day of November, A. D. 1913.

CONSTANT T. CUNDALL.
